UNITED STATES PATENT OFFICE.

JOHN M. C. HOWELL, OF MASCOT, TENNESSEE.

RAILROAD-TRACK-LAYING APPARATUS.

SPECIFICATION forming part of Letters Patent No. 739,875, dated September 29, 1903.

Application filed May 22, 1902. Serial No. 108,470. (No model.)

To all whom it may concern:

Be it known that I, JOHN M. C. HOWELL, a citizen of the United States, residing at Mascot, in the county of Knox and State of Tennessee, have invented a new and useful Improvement in Railroad-Track-Laying Apparatus, of which the following is a specification, reference being had to the accompanying drawings.

10 My invention relates to railroad-track-laying apparatus, and particularly to an improved apparatus for removing and replacing ties on railroad trestles and bridges.

The object of the invention is to provide a 15 simple and convenient mechanism by the use of which worn-out ties on railroad trestles and bridges may be removed and replaced without the removal of the track-rails and without the consequent interruption of the 20 use of the track for the passage of trains.

My present improvement may be regarded as an addition to or modification of the improvement set forth by my application, Serial 25 No. 96,375, filed in the United States Patent Office March 3, 1902.

By the use of my improved apparatus the track remains continuous and the operation may be suspended at any time for the passage 30 of a train. One of the guard-rails is removed and the tie which is to be removed is released by the withdrawal of its spikes and the slight raising of the adjacent ties, (with of course the track and guard rails.)

In the accompanying drawings, Figure 1 is 35 a plan showing a portion of a trestle or bridge structure with my improved device applied preparatory to the removal of a tie. Fig. 2 is a section on the line 2 2 of Fig. 1. Fig. 3 is a section similar to Fig. 2 and illustrates 40 a modification of the form shown by Figs. 1 and 2. Fig. 4 is a vertical section on the line 4 4 of Fig. 3. Figs. 5 and 6 illustrate another modification, Fig. 5 being a section similar to Figs. 2 and 3, and Fig. 6 being a plan of the 45 form shown by Fig. 5.

Referring to said drawings, A is one of the longitudinal sills or girders of a railway trestle or bridge.

B B are the ties resting transversely upon 50 the sills. Said ties are preferably provided with notches B' in their under faces, into which the sill extends.

C is a track-rail.

C' C' are the spikes by means of which the rail C is secured to the ties.

55

My improvement is essentially a tie-supporting structure adapted to be applied temporarily to a bridge or trestle to receive a defective tie when the latter is withdrawn from beneath the track-rails and to receive and support a new tie preparatory to drawing the latter horizontally into position beneath the track-rails to serve as a substitute for the defective tie just removed.

My improvement may be defined in a general way as consisting, functionally, of two parts, the first being means or mechanism for securing the structure in position and the second being the surface upon which the tie is moved lengthwise for removal and replacing.

60

Structurally the improved device consists of a horizontal frame bifurcated at one end, the arms of the bifurcation being suitably shaped or provided with means for securing the structure in position for use.

75

D D are side bars. These are arranged parallel to each other and joined in any suitable manner, as by means of cross-bars D'. For the purpose of facilitating the movement of the tie upon the structure rollers D² may 80 be placed transversely between said side bars. Said cross-bars and rollers are placed into that portion of the structure which is to extend outward away from the trestle or bridge, and the upper surface of said portion 85 of the structure is preferably substantially at or a little above the level of the lower face of the tie to be removed when the device is in position. Usually allowance must be made for raising the defective tie sufficiently to 90 clear the sill A. From the point where said cross-bars and rollers cease said side bars D D constitute the arms of the bifurcation of the structure. As shown in Figs. 1 and 2, said bars rise sufficiently to extend over and 95 rest upon the upper surface of the adjacent sill A. Thence said arms rise to the level of the lower face of the track-rail C. As shown in said Figs. 1 and 2, said side bars are flat pieces of metal having the outer portion and 100 the portion extending over the sill standing in a vertical plane and being then twisted so as to bring the remainder into a horizontal plane, so that the portion passing beneath

the track-rail bears flatwise against the bottom of said rail. The end of said bar passes said rail and is then bent upward and over the foot of the rail to form a hook B^3 . Upon 5 the upper face of each side bar at the side of the track-rail opposite said hook a latch E or button is pivoted in any suitable manner, as by means of a vertical bolt E' . Both ends of said button are raised sufficiently to clear the 10 foot of the rail, and one end is long enough to substantially meet the web of the rail at any point not covered by fish-plates. The other end of said button is enough shorter to permit the space between the hook D^3 and 15 said end when the latter is directed toward the rail to receive fish-plates, as well as the web of the rail. Said button and hook constitute a means for clamping the said arms to the rail.

20 By means of the hook D^3 and the latch or button E each of the side bars D is securely fastened to the track-rail. The attachment to the track-rail is one point of support and the bearing upon the sill A is another point 25 of support for the apparatus.

In putting the apparatus into position it is placed vertically with the bifurcated portion 30 downward, one arm being at each side of the tie to be removed. While the apparatus is in this position the lowermost cross-bar D may rest upon said tie. The apparatus may then be allowed to tilt with said lower cross-bar as a bearing, the upper end of the apparatus going outward and downward and the 35 free ends of the side bars going upward until they bear against the bottom of the track-rail. The apparatus is then shifted horizontally outward until the hook D^3 is in engagement with the rail C . The button or latch E 40 is then turned into engagement.

For lowering and raising the apparatus guy-ropes F may be suitably attached to the outer ends of the side bars D . Said ropes may also be used for preventing lateral movement of the outer end of the apparatus.

45 With the apparatus put into position as described the defective tie, detached from the sill and rails, as hereinbefore set forth, is drawn endwise from beneath the rails and over the sills outward over the tie-receiving portion of my apparatus, the tie being preferably supported upon said rollers D^2 until it assumes the position shown by the dotted lines in Figs. 1 and 2. The relative proportion 50 of the parts is such as to bring the outermost roller D^2 outward beyond the center of the tie when the latter is in the position indicated by the dotted lines, to the end that the tie will not tilt on account of a preponderance of weight projecting outward beyond the tie-supporting structure. The end of the tie adjacent to the track-rail is then lifted and the tie drawn up on the track and disposed of in any manner desired. The new 55 tie is then placed upon the track-rails directly above the position occupied by the defective tie just withdrawn. It is then pushed

endwise outward upon the tie-receiving portion of my apparatus until it occupies the position shown by the dotted lines in Figs. 1 70 and 2. The inner end is then allowed to descend until it is low enough to pass beneath the track-rails. The tie is then drawn endwise over the sills and beneath the track-rails to its final position. The apparatus is then removed by turning the button E so as to release the ends of the side bars, when the apparatus is moved inward. By means of the guy-ropes the outer end of the apparatus 75 is then raised and drawn inward until it stands in the vertical position upon the tie just inserted. From this position it is lifted by hand.

In the modification shown in Figs. 3 and 4 the outer support of the apparatus is not upon 80 the sill A , but in the stirrups G . Said stirrups may be of any suitable form. In the drawings they are shown in the form of the letter S , one portion extending over one of the ties adjoining the tie to be removed and 85 the other portion receiving and supporting one of the side bars D . Said stirrups may rest loosely upon the ties, or they may be fastened in any suitable manner, as by means 90 of screw-bolts G' , having handles G^2 , the screw-bolts extending through one of the arms 95 of the stirrup and bearing against one side of the tie.

Figs. 5 and 6 illustrate a modification of the mechanism for securing the side bars to 100 the track-rail. D^4 is a lug or shoulder rising from the side bar D at one side of the track-rail. At the opposite side of the track-rail is a lug D^5 , having an aperture D^6 parallel to said rail and just above the level of the ties 105 adjacent to the one which is to be removed. A shaft or bar D^7 extends horizontally through the apertures D^6 of the two side bars and projects sufficiently at each end to rest upon the adjacent ties. Said bar or shaft serves 110 to hold the side bars against the bottom of the track-rail, and when said bar is in position said lugs or shoulders prevent endwise movement of said bars.

115 It will be observed that when my apparatus is in position for use the upper surface of the track-rail is left clear, so that trains may pass without the removal of the apparatus.

120 It is obvious that the apparatus may be attached to either track-rail; but it will usually be preferable to so construct the apparatus as to adapt it for attachment to the track-rail adjacent to the side of the bridge or trestle from which the tie is to be withdrawn. In this form the apparatus is shorter, and hence 125 more easily handled. It is also obvious that the apparatus may be attached to or engaged by any rail other than a track-rail extending longitudinally over the trestle or bridge structure.

130 I claim as my invention—

1. A railroad-track-laying apparatus consisting of a frame or support having a tie-receiving surface at one end and having at the

other end two parallel arms suitably spaced to extend at each side of a tie in a railroad trestle or bridge and each having means for forming engagement with a rail extending longitudinally over the trestle or bridge, substantially as described.

2. A railroad-track-laying apparatus consisting of a bifurcated structure having arms or side bars suitably shaped and separated to extend over and rest upon a railroad trestle or bridge sill at each side of a tie and said structure having a tie-receiving surface lower than the portions of said arms which are to rest on said sill, and said arms being suitably shaped for engagement with a rail extending longitudinally over the trestle or bridge, substantially as described.

3. A railroad-track-laying apparatus consisting of a bifurcated, tie-sustaining structure having arms or side bars suitably separated to extend at each side of a tie in a railroad trestle or bridge, and mechanism applied to said arms for clamping said arms to a rail extending longitudinally over the trestle or bridge structure, substantially as described.

4. A railroad-track-laying apparatus consisting of a bifurcated, tie-sustaining structure having arms or side bars suitably separated to extend at each side of a tie in a railroad trestle or bridge, and mechanism applied to said arms, for clamping said arms to the foot of a track-rail extending longitudinally over the trestle or bridge structure, substantially as described.

35 5. A railroad-track-laying apparatus consisting of a bifurcated, tie-sustaining structure having a horizontal tie-receiving surface and having arms or side bars suitably separated to extend at each side of a tie in a rail-

road trestle or bridge, said arms rising approximately the height of a tie, and provided with means for forming an engagement with a rail extending longitudinally over the trestle or bridge structure, substantially as described.

6. A railroad-track-laying apparatus consisting of a bifurcated structure having a horizontal tie-receiving surface and having arms or side bars suitably separated to extend at each side of a tie in a railroad trestle or bridge, said arms rising above said tie-receiving surface approximately the height of a tie, and having a fixed part adapted to rise at one side of a rail extending longitudinally over the trestle or bridge structure, and a shiftable part located adjacent to said fixed part, substantially as described.

7. A railroad-track-laying apparatus consisting of a bifurcated structure having a horizontal tie-receiving surface and having arms or side bars suitably separated to extend at each side of a tie in a railroad trestle or bridge, said arms rising above said tie-receiving surface approximately the height of a tie, and having a fixed part adapted to rise at one side of a rail extending longitudinally over the trestle or bridge structure, and a button located at the opposite side of the space which is to be occupied by the rail, substantially as described.

In testimony whereof I have signed my name, in presence of two witnesses, this 10th day of May, in the year 1902.

JOHN M. C. HOWELL.
